UNITED STATES PATENT OFFICE

2,609,196

DEVICE FOR IMPARTING A TUMBLER MOTION TO VERTICAL STRUCTURAL PARTS

Jacob Wieland, Gorinchem, Netherlands, assignor to De Vries Robbe & Co. N. V., Arkelschedijk, Gorinchem, Netherlands

Application December 24, 1947, Serial No. 793,644
In the Netherlands June 5, 1944Section 1, Public Law 690, August 8, 1946
Patent expires June 5, 1964

5 Claims. (Cl. 268—74)

1

This invention relates to operating arrangements for covering or uncovering an opening in a vertical wall by means of a rigid closure member such as a door of the slide-up turn-over type. More particularly, the invention relates to doors, an intermediate portion of which is hinged by one or more arms to the wall and which are slidably guided with their lower end along the said wall so that the doors will swing about said arm or arms when moved from one position into the other.

Small doors or hatches can, of course, be manually opened and closed without much difficulty, but for larger units special operating devices are usually required. There are already known operating devices comprising an endless chain or cable secured to the top edge of the door for exerting a substantially horizontal pull upon the door so as to move the same into an open position. There are further known operating systems in which a vertical force is applied to the bottom of the door for pulling the same into an open or closed position as the case may be. There are also known various counterweight arrangements for balancing the door. However, all these known arrangements require the application of a comparatively large force and tend to cause jerky door movements since the coupling forces applied to the door do not act in the most favorable direction as will be more fully explained hereinafter.

One of the principal objects of the present invention is to provide an operating arrangement by which a comparatively heavy door can be smoothly opened and closed.

Another object of the invention is to provide an operating arrangement which permits a smooth opening or closing of the door by the application of comparatively small force since the applied forces act upon the door in the most favorable direction.

Other and further objects, features and advantages of the invention will be pointed out hereinafter and set forth in the appended claims forming part of the application.

In the accompanying drawing several now preferred embodiments of the invention are shown by way of illustration and not by way of limitation.

In the drawing:

Fig. 1 is a diagrammatic view of a door in substantially closed position showing the direction of the forces applied to the door.

Fig. 2 is a diagrammatic view of the door in substantially opened position also showing the direction of the forces applied to the door.

2

Fig. 3 is a diagrammatic view of an operating arrangement according to the invention for closing a door, and

Fig. 4 is a diagrammatic view of an operating arrangement according to the invention for opening the door.

Referring first to Figs. 1 and 2 in detail, these figures each show a vertical wall 1 having an opening 2 therein. This opening can be covered or uncovered by a rigid door 3. The door is supported by one or more arms 4 which are hinged at 10 to an intermediate point of the door and at 11 to wall 1. As will be noted, arms 4 are hinged to the wall at a point above the upper edge of the wall opening 2 and to the door near the center of gravity thereof. The lower end of each door supports one or more rolls 5 by means of which the doors are guided in the frame of the door opening 2 and alongside of wall 1 so that the doors can move in a manner which will be obvious from an examination of Figs. 1 and 2.

The present invention is concerned with the opening and closing of doors suspended as explained in connection with Figs. 1 and 2.

Let it now be assumed that it is desired to open the door of Fig. 1 and that for this purpose an upwardly directed vertical force is applied to the lower edge of the door. Such force will result in an opening of the door but it has to be a very large force since the useful component of force is bound to be small due to the nearly vertical position of the door. Furthermore, the door movement is likely to be jerky in view of the large forces involved. If now, a substantially horizontal force is applied to the upper edge of the door as indicated by the arrow P, it will be found that the door can be easily and smoothly opened since now the component or force acts in a more favorable direction. Turning now to Fig. 2, it will be apparent that a horizontal force applied to the upper edge of the door will close the same but must be large and will cause the jerky door movements. If, however, a vertical downwardly directed force is applied to the lower edge of the door as indicated by arrow P', the door can be easily and smoothly closed.

The foregoing analysis of the effective forces show that by judicious application of horizontal and vertical forces, a heavy door can be smoothly and easily opened and closed.

Figs. 3 and 4 show operating arrangements by which the most favorable vertically and horizontally acting forces can be applied to a door suspended as previously explained.

Referring first to Fig. 3, which shows a door closing arrangement, a cable or chain 7 is se-

cured at 9 to the upper edge of the door 3 and guided over stationary pulleys 12 and 13 to a movable pulley 14. Similarly, the lower edge of the door is secured to a cable 8 which is guided over fixed pulleys 15 and 16 to the loose pulley 14. Cables or chains 7 and 8 are shown as being joined so that they may be considered as an endless chain.

If it is now desired to close the door a pull is applied to pulley 14 in a direction away from wall 1 as indicated by arrow 6. Consequently, cable section 7' exerts a substantially horizontal pull upon the upper edge of door 3 and cable section 8' a downwardly directed substantially vertical pull upon the lower edge of the door. As will appear from the previous discussion of Figs. 1 and 2, the horizontal and vertical forces simultaneously applied to the door will turn the same smoothly and easily. It will further be apparent that the fixed pulleys 12 and 15 are the essential ones which determine the directions of the forces.

According to the opening arrangement according to Fig. 4, the upper end of door 3 is fastened at 9 again to a cable or chain 7 which is guided over fixed pulleys 17 and 18. The lower end of the door is secured to cable 8 which is guided over a fixed pulley 19. The two cable ends 7 and 8 are joined over the loose pulley 14.

It will now be evident that movement of the loose pulley 14 in a direction away from wall 1, as indicated by arrow 6, causes cable section 7' to apply a substantially horizontal force to the upper edge of the door and cable section 8' to exert an upwardly directed substantially vertical force to the lower edge of door 3. It will again be apparent that pulleys 17 and 19 determine the direction of the forces. As will further be evident a horizontal and vertical force are simultaneously applied to the door in the most favorable direction.

The previous description will also make it clear that the pull direction does not have to be applied in the direction of the arrows 6. For instance, in Figs. 3 and 4 pulley 14 could be pulled in a direction substantially vertically upward. Finally, it will be understood that pulley 14 is merely provided to facilitate the application of force to the endless cables.

While it is possible to provide either the closing arrangement of Fig. 3 or the opening arrangement of Fig. 4, in practice it will generally be preferable to provide both operating arrangements. Furthermore, conventional counterweight systems may be provided.

What is claimed is:

1. An operating arrangement for covering and uncovering an opening in a vertical wall by a rigid slide-up, turn-over closure member hinged at an intermediate point by at least one arm to said wall and slidably guided at its lower end along said wall for swinging and sliding the closure member into an open and a closed position respectively, the said operating arrangement comprising first flexible traction means attached to the lower edge of the closure member, second flexible traction means attached to the upper edge of the closure member, first stationary guide means guiding the first traction means for exerting a pull upon the lower edge of the closure member in substantially vertical direction, second stationary guide means guiding the second

traction means for exerting a pull upon the upper edge of the closure member in a substantially horizontal direction, said two traction means being joined at their free ends, and third movable guide means guiding said joined traction means and disposed to exert a pull on both said traction means for the purpose of effecting the aforesaid vertical and horizontal pulls in response to a displacement of the third guide means, thereby moving the closure member from one position into the other.

2. An operating arrangement for covering and uncovering an opening in a vertical wall by a rigid slide-up, turn-over closure member hinged at an intermediate point by at least one arm to said wall and slidably guided at its lower end along said wall for swinging and sliding the closure member into an open and a closed position respectively, comprising a flexible cable attached at one end to the lower edge of the closure member and at the other end to the upper edge of the closure member, a first stationarily mounted pulley guiding the cable section attached to the lower edge of the closure member for exerting a pull upon the lower edge of the closure member in a substantially vertical direction, a second stationarily mounted pulley guiding the cable section attached to the upper edge of the closure member for exerting a pull upon the upper edge of the closure member in a substantially horizontal direction, and a third movably mounted idler pulley guiding the cable for exerting a simultaneous pull upon the aforesaid cable sections for the purpose of effecting the aforesaid vertical and horizontal pulls in response to a displacement of the third pulley, thereby moving the closure member from one position into the other.

3. An operating arrangement as described in claim 2 for closing said closure member, wherein the first pulley is disposed in a plane below the lower edge of the closure member in any angular position of the said edge.

4. An operating arrangement as described in claim 2 for opening said closure member, wherein the first pulley is disposed in a plane above the lower edge of the closure member in any angular position of the said edge.

5. An operating arrangement as described in claim 1, wherein said arm is hinged to the vertical wall above the upper edge of the wall opening and to the closure member near the center of gravity thereof.
